STAMP PAD

Whitney K. Munson, Orange, N. J., assignor to
 Munson Stamp Pad Co. Inc., New York, N. Y., a
 corporation of New York

Application September 17, 1930, Serial No. 482,406

5 Claims. (Cl. 91—54.5)

The invention in certain of its aspects relates to inking pads adapted to be used for supplying ink to stamps in the well known manner, and in certain other aspects the invention relates to containers for pads of the above character. Inking pads have heretofore been proposed wherein the absorbent material was contained within metal frames adapted to be inserted in suitable containers, but such metal frames have 5 substantially reduced the active area of the pad over which the stamp could be effectively inked, and one of the objects of the present invention is to provide an inking pad of the above type which will avoid this objection. Other objects 10 of the invention are to provide an inking pad and container therefor of such construction that the pad will be securely and yet removably held in proper position with respect to the container in a simple manner; and to provide a container 15 having a cover construction and releasable catch or latch therefor, having certain advantages such as are hereinafter referred to in greater detail. Further objects and advantages of the invention will be in part obvious and in part 20 specifically referred to hereinafter. In the drawing—

Fig. 1 is a plan view of an inking pad constructed in accordance with the invention;

Fig. 2 is a section on line 2—2 of Fig. 1 looking 25 in the direction of the arrows.

Fig. 3 is a perspective view of a container adapted to be used in conjunction with the pad shown in Figs. 1 and 2.

Fig. 4 is a cross sectional view of such 30 container.

In accordance with the present invention I provide a frame of relatively stiff material, for example, a piece of metal wire 1 which may be suitably welded or soldered together at its ends, and which encloses a pad 2 of absorbent material, to hold the latter in shape when subjected 35 to the repeated blows of the stamp.

A sheath or envelope 3 of suitable fabric encloses both the frame 1 and pad 2, the frame 40 serving to keep the envelope 3 stretched taut, and the envelope 3 being preferably tubular and having its ends closed by rows of stitching 45 (Fig. 1).

As an additional feature to insure tautness of 50 the envelope 3, the frame 1 may be made of metal possessing a certain amount of resiliency, and the sides 5 and 6 may be somewhat bowed or distorted when the frame is placed within the envelope 3, whereby the pressure exerted on 55 the sheath or envelope 3 by such bowed or dis-

torted portions, will assist in maintaining the necessary tautness.

In the use of an inking pad of the above nature the ink will permeate throughout the entire outer surface of the pad, and the stamp will be adequately inked even though applied adjacent the edge of the pad, as often happens when stamps are operated rapidly. The pad also is exceedingly simple and economical in construction, and the two inking surfaces made 10 up by the envelope 3 are kept smooth, and the absorbent pad 2 is kept in proper shape by the frame 1, over long periods of use.

An inking pad of the above type may be placed in a container which, as shown in Figs. 3 and 4, 15 is preferably made of rubber or rubber-like material, and provided with a base 7 having a somewhat yieldable flange 8 projecting up from its upper surface to provide a recess 9 adapted to receive the inking pad above described. This 20 flange 8 encircles the pad and preferably grips the latter elastically to assist in holding the pad in proper position. One or more wells 11 filled with absorbent material 11a, may be provided 25 in the bottom of the recess 9 to receive ink and feed the ink up to the inking pad.

I prefer to provide the frame 1 with one or more lugs or projections 10 (Fig. 1) which may be formed merely by flattening down the metal at the desired points, which will engage recesses 30 10a in the walls of recess 9 to hold the inking pad securely in the latter. The pad may be pried loose, however, whenever desired, the flange 8 being merely slightly stretched when 35 the pad is placed in position in recess 9.

I prefer also to provide the container with a cover which is releasably held in closed position and which will spring open when released. In the specific form of the invention which is illustrated, a metal cover 12 is provided having side-walls 13 pivoted on a rod 14 shown as molded within a shoulder 15 and ears 15a extending up from the container base 7. Suitable springs such as the spiral springs 16 shown in Fig. 3, 40 urge the cover 12 toward open position, but the cover may be frictionally held closed by a catch or latch 17 which in the illustrated form of the invention is shown as made integral with the base of the container and which will therefore 45 be somewhat flexible. When this catch 17 is flexed away from the cover 12, the latter will fly open to the position shown in Fig. 3, the back wall 19 of the cover being shaped to act as a stop when the cover is open. Preferably the 50 55

catch 17 is reinforced by a flexible metal piece 20 as shown in Fig. 4.

The cover 12 is preferably provided with a raised portion or rib 21 conforming in shape to 5 the flange 8 which encloses the pad, and pressing down on such flange when the cover is in closed position, to seal the pad from the air, and insure that the cover does not press down on the pad and thereby become soiled.

10 Whenever the pad is to be used, it may be easily exposed by drawing back the catch 17 which will cause the cover 12 to flip to open position.

15 While a specific form of the invention has been described above, it will be understood that many changes may be made therein without departing from its principles as set forth in the appended claims.

20 What I claim is:

1. A stamp pad having a relatively stiff frame open on both faces, absorbent material enclosed by said frame and having its opposite faces lying substantially in the planes of the respective faces 25 of the frame, and a fabric sheath enclosing said frame and overlying the opposite faces of said absorbent material to hold the absorbent material in its aforesaid position, said frame having one or more resilient portions exerting tension on 30 the fabric envelope to hold the latter taut.

2. A stamp pad having a relatively stiff frame, absorbent material enclosed by said frame, and a fabric sheath enclosing said frame and absorbent material to hold the absorbent material 35 in position therein, a rubber like base having a recess adapted to receive the pad and the frame

of the pad being provided with one or more projections adapted to engage the walls of the base which bound said recess to hold the pad removably in position.

3. A pad holder having a base provided with a flange adapted to enclose a pad, and a cover associated with said base and adapted to overlie a pad contained in the base when the cover is in closed position, said cover having side-walls adapted to enclose said flange when the 10 cover is in closed position and also having a raised portion engaging the top of said flange when the cover is in closed position, to space the part of the cover enclosed by said raised portion, from the area of the base which is en- 15 closed by said flange.

4. In combination a stamp pad having a relatively stiff frame, absorbent material located within and bounded by said frame, a base member having a recess adapted to receive said pad 20 and provided with elastic walls surrounding said recess which are stretched around said frame when the pad is placed in position in said recess.

5. A pad holder comprising a base having a 25 recess adapted to receive a pad, said base being of rubber like material, a cover for said recess having means yieldably urging the same toward open position, said base being provided with an integral flexible catch of rubber-like material 30 adapted to frictionally hold said cover in closed position and to release the same when said catch is flexed, said catch having a reinforcing member embedded therein and extending into said base. 35
